CLAIM

The ornamental design for a control assembly of an agricultural work vehicle, substantially as shown and described.

DESCRIPTION

FIG. 1 is a perspective view of a control assembly of an agricultural work vehicle;

FIG. 2 is a top view of the control assembly;

FIG. 3 is a left side view of the control assembly;

FIG. 4 is a detailed left side view of the control assembly, taken within line 4-4 of FIG. 3; and,

FIG. 5 is a back view of the control assembly.

Phantom lines, where utilized, are for illustrative purposes only and form no part of the claimed design.

1 Claim, 5 Drawing Sheets
